UNITED STATES PATENT OFFICE.

ELMER R. MARTIN, OF ELGIN, ILLINOIS, ASSIGNOR TO ELGIN STREET SWEEPER CO., OF ELGIN, ILLINOIS, A COPARTNERSHIP CONSISTING OF CHARLES A. WHITING, JAMES TODD, AND DANIEL M. TODD.

REFUSE GUIDE FOR STREET SWEEPERS.

Application filed November 29, 1920. Serial No. 426,918.

To all whom it may concern:

Be it known that I, ELMER R. MARTIN, citizen of the United States, residing at Elgin, in the county of Kane and State of Illinois, have invented certain new and useful Improvements in a Refuse Guide for Street Sweepers; and I do hereby declare the following to be a full, clear, and exact description of the invention, such as will 5 enable others skilled in the art to which it appertains to make and use the same.

My invention relates to street sweeping machines of the general class in which the refuse is swept off the street by a rotating broom and is then carried by a conveyer to a suitable hopper. With such machines, it is not practical to have either the conveyer or the conveyer casing extend down to the surface of the street, hence it has been customary to provide a drag flap or dirt pan which substantially forms an extension of the conveyer casing towards the sweeping broom and which guides the swept refuse towards the conveyer. Such dirt pans as 15 commonly employed slope down rearwardly of the machine towards the sweeping brush and have been found open to three serious objections:

The first is that such a drag pan must be 20 lifted before the driver of the machine can back the latter without jamming the pan into the surface of the street and therefore risking serious damage, so that, the machine cannot be manipulated as freely as is often 25 desirable on crowded streets. The prevention of damage to the machine therefore depends on the care exercised in the above respect by the driver, and even a careful driver may not be able to prevent the same 30 if the machine slips backward when halted on an upward slope.

In the second place, stones, bricks or other 35 heavy objects of a size and weight not readily handled by the machine are apt to 40 raise the flap or dirt pan unduly, thereby causing the broom to project refuse with considerable violence forwardly of the machine under this pan, or in other words, spoiling the proper control of the directing 45 of the refuse towards the conveyer.

In the third place, the thickness of metal 50 required to insure good wearing qualities in such a drag flap or dirt pan makes this so heavy that it will not be lifted by light ob-

jects like papers or fallen leaves. Consequently, in the autumn season, the dragging dirt pan will slide the fallen leaves in front of it until they are tightly packed under this pan and jam the pan against the broom, so that the broom will only project these 60 leaves further forward along the street under the pan instead of directing them towards the conveyer.

My present invention aims to overcome all of the above named objections by providing 65 a substitute for the customary drag flap or dirt pan, which substitute refuse guide will permit a backing of the machine without a risk of damaging any part of either machine or the street; which substitute will also ride 70 freely over fallen leaves or the like, and which will automatically guide bricks or stones out of its path so as to prevent the latter from interfering with the normal operation of the machine. Furthermore, my 75 invention aims to provide this substitute part in a form which will not easily be damaged and which will prevent the presence of mud or clay from interfering with the ready forwarding of the refuse to the 80 conveyer. Still further and more detailed objects will appear from the following specification and from the accompanying drawings, in which

Fig. 1 is a central and longitudinal section 85 of a portion of a street sweeping machine equipped with my invention.

Fig. 2 is a slightly enlarged transverse section through the same, taken along the correspondingly numbered line of Fig. 1. 90

Fig. 3 is a similar vertical section taken along the correspondingly numbered line of Fig. 1.

While my invention may be applied with 95 substantially equal facility to street sweeping machines differing considerably in their construction, it is particularly applicable to machines of the type disclosed in U. S. Patent No. 1239293 issued September 4, 1917 to J. M. Murphy. I am therefore illustrating and describing my invention in an embodiment suitable for the machine of this patent, although I do not wish to be limited to this particular application of my invention.

In the drawings, Fig. 1 shows portions of the street sweeper including the main brush or broom 1 which is mounted on a continu-

ally rotating shaft 2 and which directs the sweepings forwardly of the machine and towards the lower end of an inclined conveyer mechanism. This conveyer mechanism includes a continuously moving conveyer belt 3 arranged for lifting and conveying the refuse to the usual hopper of such a machine. This belt has its lower and rear end disposed in the path in which the broom projects the refuse off the street, and also disposed above the bottom of a casing 4, which bottom prevents the refuse from dropping below the conveyer to the street. To clear stones or other objects on the street, it is customary to have the bottom of the casing which houses the conveyer spaced somewhat from the street, and it is therefore necessary to guard against having a part of the loosened refuse swept by the broom forwardly of the machine under the bottom of this casing. To avoid the heretofore recited objections to the use of drag flaps or flat dirt pans for such a purpose, I substitute a guard or refuse guide in the form of a roller 5, which is here shown as consisting of a steel tube mounted on heads 6 which have a shaft 7 extending through the same. This shaft 7 is journaled in a pair of brackets 8, each of which brackets slopes up and forwardly of the machine and is connected at its upper end through a pivot pin 9 to the adjacent side plate 10 of the casing which houses the conveyer. The roll 5 is desirably larger in diameter than the distance between the surface of the street and the bottom 4 of the conveyer casing, and also is desirably disposed rearwardly of this bottom, so that it partly underhangs the broom 1 and hence effectively closes the opening below the conveyer casing to prevent the forward projection of refuse through this opening by the broom of the machine.

With the parts thus arranged, it will be evident that the inclined portions of the bracket 8 form links which will pull the roller along with the machine while permitting the roller to move up and down in passing over refuse on the street. Moreover, I desirably provide lost motion between each of the pivot pins 9 and one of the parts connected by the latter, so that the two bracket arms 8 can move somewhat independently of each other, thereby permitting the shaft 7 to tilt more or less transversely of the street according as the roll encounters variations in the street level. I also desirably provide lateral guards in the form of a pair of side plates 11, each of which is pivoted upon the inner end of the hub of one of the brackets 8 and each of which has a portion disposed between the adjacent side plate 10 of the conveyer casing and one end of the roll, whereby the side plates are maintained in a substantially vertical position. The bore entered by the inner end of the adja-

cent bracket arm 8 is so positioned in the side plate 11 that the forward end of this side plate is continuously held clear of the ground, while the rear end may drag freely on the surface of the street. Thus arranged, the two side plates 11 form lateral guards for confining the projected refuse laterally of the street, while the tube 5 of the roll forms a guard for preventing the projected refuse from being projected horizontally under the conveyer casing and also deflects some of the projected refuse upon the conveyer, as shown by the arrow A in Fig. 1. The roll therefore acts in a general manner similar to the dragging dirt pan formerly used for this purpose, but readily permits the machine to be backed without jamming any part into the street and therefore without causing damage of any kind.

Moreover, when there are light and substantially flat objects on the surface of the street, such as papers or fallen leaves, the rolling progress of the roller will cause the latter to press the rear edges of such objects down when it first encounters them, thereby preventing them from slipping and causing the roller to roll over them instead of sliding them ahead of this guard as has been found true with dirt pans of the drag-flap type. Then, as the roller is passing beyond such fallen leaves or papers, it presses down the forward edges of the latter, and in doing so flexes these leaves so as to spread their rear edges apart upwardly. Consequently, these separated rear edges are readily engaged by the broom in spite of the light weight of such leaves, so that with my arrangement the ordinary revolving brush or broom readily projects fallen leaves upon the conveyer.

To make the guard or guide of my invention still more effective, I also desirably equip it with means tending to move refuse longitudinally of the roll, and for this purpose I preferably employ a steel ribbon 12 coiled in the form of a spiral about the tube 5 and secured to the latter, the direction of the spiral being such that when the roll is rotated by contact with the surface of the street, the spiral will have a cam action tending to move objects towards the left of the machine, or away from the curb, since such machines are usually driven along the right-hand side of the street. In practice, this spiral ribbon serves a double purpose, one being that of preventing lumps of mud, clay or the like from being carried over the top of the roll by sticking to the latter and then being rotated as a cylinder between the roll and the rear end of the bottom 4 of the conveyer. Such an action is effectively prevented by the ribbon, since the latter will move any adjacent matter towards one side of the machine and will therefore bunch it up so that the refuse following it will read-

ily knock it loose and cause it to be projected either upon the top of the conveyer belt or at least into the path of the usual projections on this belt.

5 The second purpose accomplished by this spiral winding is that of removing unduly large and incompressible objects out of the path of the machine. Where such objects, as for example bricks have been left on the 10 street, the ordinary drag flap would be raised by the same out of effective position and might even be lifted into such forcible engagement with the broom as to cause damage to both parts. With my spirally ribbed roll, a 15 brick 13 encountered on the street will be engaged by an edge of the spiral ribbon after the manner shown in Fig. 3, and the cam action of this spiral will then slide the brick to the left of the machine or entirely out of 20 the path of both the roll and the broom, so that the presence of such objects on the street will not interfere in the least with the effective action of the machine. However, with a relatively thin spiral ribbon, this cam action 25 will not appreciably affect smaller articles of refuse on the street and hence will not interfere with the rolling of the guard over the same.

However, while I have illustrated and 30 scribed my invention in an embodiment including a hollow roll and including a certain arrangement of the floating mounting for this roll, I do not wish to be limited to the details of the construction and arrangement 35 thus disclosed, it being obvious that the same might be modified in many ways without departing from the spirit of my invention or from the appended claims.

I claim as my invention:

40 1. In a street sweeper, a refuse lifting conveyer, a rotating broom disposed for sweeping refuse off the street directly upon the conveyer, and a revoluble guard disposed between the bottom of the conveyer 45 and the broom for preventing the projecting of refuse under the bottom of the conveyer by the broom, the said guard being rotated by frictional engagement with the street.

2. In a street sweeper, a refuse lifting 50 conveyer, a rotating broom, and a revoluble guard disposed between the bottom of the conveyer and the broom and continuously rolling upon the surface of the street, the guard having a substantially cylindrical 55 peripheral surface adapted to deflect broom projected refuse towards the conveyer.

3. In a street sweeper, a refuse lifting 60 conveyer belt, a casing housing the belt, a revoluble guard disposed between the broom and the bottom of the said casing, and means for freely journaling the guard while permitting the latter to roll on the surface of the street and to be revolved by contact with the latter.

65 4. In a street sweeper, a refuse lifting

conveyer belt, a casing housing the belt, a revoluble guard disposed between the broom and the bottom of the said casing, and means for journaling the guard while permitting the latter to roll on the surface of the street 70 and while permitting relative raising or lowering of opposite ends of the guard.

5. In a street sweeper, a rotating broom, a refuse lifting conveyer mechanism forwardly of the broom, a roller normally engaging the surface of the street and disposed forwardly of the bottom of the broom and rearwardly of the lower end of the conveyer mechanisms, and means for journaling the roller, the said means including links 80 inclined downwardly toward the axis of the roller.

6. In a street sweeper, a rotating broom, a conveyer mounted forwardly of the broom and terminating above the surface of the 85 street and disposed in the direct path of refuse swept up by the broom, and means operatively closing the opening below the conveyer mechanism in front of the broom and formed for deflecting broom-projected 90 refuse directly upon the conveyer, the said means comprising a revolubly mounted member underhanging the broom and having its axis parallel to that of the broom.

7. In a street sweeper having a rotating 95 broom disposed behind a conveyer mechanism which terminates at a distance above the level of the street, common means for preventing the broom from projecting refuse through the gap below the said mechanism 100 and for moving refuse transversely of the path of the sweeper.

8. In a street sweeper having a rotating broom disposed behind a conveyer mechanism which terminates at a distance above 105 the level of the street, revoluble means for preventing the broom from projecting refuse through the gap below the said mechanism and for moving relatively large objects 110 out of the path of the broom.

9. In a street sweeper, a refuse lifting 115 conveyer, a rotating broom, and a rovoluble guard disposed between the bottom of the conveyer and the broom for preventing the projecting of refuse under the bottom of the conveyer by the broom, and cam means upon the guard for moving refuse transversely of the path of the sweeper.

10. In a street sweeper having a rotating broom disposed behind a conveyer mechanism which terminates at a distance above 120 the level of the street, a floatingly mounted roller disposed for preventing the broom from projecting refuse through the gap below the said mechanism, and a spiral ribbing 125 on the roller for moving relatively large objects longitudinally of the roller.

11. In a street sweeper having a rotating broom disposed behind a conveyer which terminates at a distance above the level of 130

the street, common smooth-surfaced means for deflecting directly upon the conveyer the refuse projected by the broom toward the gap below the said mechanism, and for flexing superposed leaves or the like to spread the rear edges thereof before they are engaged by the broom.

12. In a street sweeper having a rotating broom disposed behind a conveyer mechanism which terminates at a distance above the level of the street, single floatingly mounted revoluble means for guiding broom-projected refuse to the conveyer mechanism, the said means comprising a member having a general cylindrical contour and of sufficiently small diameter to flex superposed leaves or the like while rolling over the same so as to spread the rear edges of the leaves before they are engaged by the broom.

13. In a street sweeper having a rotating broom disposed behind a conveyer mechanism which terminates at a distance above the level of the street, floatingly mounted means arranged both for guiding broom-projected refuse to the conveyer mechanism and for moving refuse transversely of the path of the sweeper.

14. In a street sweeper having sweeping means arranged for projecting refuse directly upon a conveyer terminating above the conveyer, roller means effectively closing the space below the conveyer against the projecting of refuse through the said space

by the sweeping means and rotated by frictional engagement with the street surface, and side plates supported by the roller means for laterally confining the broom-projected refuse.

15. In a street sweeper having a conveyer mechanism housed by a casing having side plates, and having sweeping means for projecting refuse towards the conveyer mechanism, rolling means effectively closing the space below the said casing against the projecting of refuse through the said space by the sweeping means; and side plates each supported at one end conjointly with the roller means and each dragging at its other end on the street, for laterally confining the projected refuse.

16. In a street sweeper having a conveyer mechanism housed by a casing having side plates, and having sweeping means for projecting refuse towards the conveyer mechanism, rolling means effectively closing the space below the said casing against the projecting of refuse through the said space by the sweeping means; flanges on the roller means adjacent respectively to the side plates of the casing, and auxiliary side plates respectively disposed between the aforesaid side plates and the said flanges for laterally confining the projected refuse.

Signed at Elgin, Illinois, November 26th, 1920.

ELMER R. MARTIN.
